[57] CLAIM

The ornamental design for a recreational vehicle, as shown and described.

DESCRIPTION

FIG. 1 is a side and front perspective view of a recreational vehicle illustrating my new design as seen from the right front.

FIG. 2 is a side elevational view thereof as seen from the right.

FIG. 3 is a side elevational view thereof as seen from the left, FIG. 4 is a top plan view thereof.

FIG. 5 is a front elevational view thereof; and, FIG. 6 is a rear elevational view thereof.

The bottom of my new design is unornamented.
